UNITED STATES PATENT OFFICE.

SIEGMUND A. DOBER, OF WOODHAVEN, NEW YORK.

DESIGN FOR A PIPE STEM.

Application filed October 16, 1925. Serial No. 15,152. Term of patent 14 years.

To all whom it may concern:

Be it known that I, SIEGMUND A. DOBER, a citizen of the United States, and a resident of Woodhaven, Long Island, in the county of Queens and State of New York, have invented a new, original, and ornamental Design for Pipe Stem, of which the following is a specification, reference being had to the accompanying drawing, forming part thereof, wherein—

Figure 1 is a plan view of a pipe stem showing my new design;

Figure 2 is a side elevation of the same.

I claim:

The ornamental design for a pipe stem as shown.

SIEGMUND A. DOBER.
